UNITED STATES PATENT OFFICE.

HALBERT K. HITCHCOCK, OF PITTSBURGH, PENNSYLVANIA, ASSIGNOR OF ONE-HALF
TO HITCHCOCK EXPERIMENT COMPANY, A CORPORATION OF NEW JERSEY.

APPARATUS FOR MAKING SHEET GLASS

Application filed February 5, 1925. Serial No. 7,039.

To all whom it may concern:

Be it known that I, HALBERT K. HITCHCOCK, a citizen of the United States, and a resident of Pittsburgh, in the county of 5 Allegheny and State of Pennsylvania, have made a new and useful invention in Improvements in an Apparatus for Making Sheet Glass, of which the following is a specification.

10 The invention relates to apparatus for making sheet glass in a continuous operation by flowing it from a tank between a pair of sizing rolls. It has for its principal objects, the provision of improved rolling 15 means, permitting the use of smaller rolls than have heretofore been employed without any substantial deformation of such rolls, so that the rolling pass between the rolls is maintained constant; the provision 20 of rolling means of the type specified wherein the crumbling or washing away of the clay lips of the outlet slot coating with the rolls and the consequent contamination 25 of the glass, is reduced to a minimum; and the provision of improved rolling means 30 wherein the formation of severely chilled glass along the lines of approach between the rolls and clay lips is reduced in quantity, thus eliminating to a large degree 35 the ream or other similar defects in the glass sheet or ribbon due to this cause. Certain embodiments of the invention are 40 illustrated in the accompanying drawings wherein:

45 Figure 1 is a partial side elevation and partial vertical section illustrating the invention. Fig. 2 is a section on the line II—II of Fig. 1. Fig. 3 is a plan view. And Fig. 4 is a vertical section through a modified construction.

Referring to the drawings, 1 is the outlet end of a tank containing a molten bath 50 of glass and having an outlet slot 2 through one side, such slot being formed in the clay member 3 supported by the metal framework 4 and vertically adjustable in position by suitable chain supports above, not shown. The flow of glass through the outlet may be cut off, when this becomes desirable for 55 any purpose, such as for replacements or repairs, by means of the water cooled gate 5, also supported for vertical movement from above by means not shown. Extending transversely of the front of the furnace 58 is a track 6 upon which is mounted a car 7

carrying the framework 8 upon which the rolling mechanism is mounted. This framework is mounted slidably in the guides 9 (Fig. 2), so that the apparatus may be adjusted toward and from the front of the 60 furnace for the purpose as hereinafter more fully set forth, this adjustment being accomplished by means of the screws 10 threaded into the framework 8 having their heads 11 swivelled in suitable brackets or 65 flanges 12 extending upwardly from the bottom plate of the car body. Pivoted at each side of the supporting framework 8 is a bell crank lever having the horizontal arm 13 and the downwardly 70 extending arm 14, such levers being pivoted on the axles 15 of the supporting or backing 75 rolls 16.

The lower ends of the levers carry the sizing or dimensioning rolls 17 between 75 which the ribbon of glass 18 is continuously formed. In order to adjust the rolls 17 toward and from each other, the horizontal ends 13 of the bell crank levers are connected by means of the vertical rods 19, 80 such rods being threaded at their ends into the blocks 20 with right and left hand threads and being swivelled against vertical movement by means of the discs 21 lying in suitable recesses in the side walls of the 85 framework 8. These discs are provided with perforations, as shown, for the reception of an adjusting bar.

The shafts 15 of the backing rolls project laterally through one of the side members of the supporting framework, as indicated in Fig. 2, and these ends are connected by suitable tumbler rods with operating mechanism for turning the rolls 16, and these rolls in turn drive the sizing 90 rolls 17 through the intermediary of the spur gears 22 and 23 carried respectively by the axles of the rolls 16 and 17. The rolls 17 are made hollow and water cooled 95 by means of water supply connections 24 100 swivelled to their ends in such manner as to provide a continuous flow of water through the rolls.

The glass as it emerges from the sizing 105 rolls is received upon the series of fluid cooled rolls 25 suitably driven and adapted to conduct the sheet continuously into a roller lever located with its inlet end closely adjacent to the rolling apparatus. The glass is continuously carried through this 110

leer and is annealed and cooled to a point where it may be cut off and handled without difficulty at the outlet end of the leer.

The apparatus as above described permits the use of sizing rolls 17 of relatively small diameter, since the backing or supporting rolls hold the sizing rolls against deformation and thus obviate the necessity for using sizing rolls of large diameter, such as have heretofore been considered necessary in order to maintain a pass between the rolls of uniform width and not subject to variation incident to stresses set up in the roll by pressure and temperature conditions.

15 These rolls of smaller diameter are advantageous as compared with rolls of larger diameter in that the clay lips at 26 may be made relatively blunt as compared with the lips employed with larger rolls in which the 20 lips are necessarily extended somewhat into the triangular recess between the two rolls. The blunter lips crumble and wear away less than the sharper ones, so that after a continued period of use, the enlargement of 25 the clearance between the rolls and the lips is less and the formation of mechanical ream incident to the formation of highly chilled glass at these points is reduced. With the larger rolls, the sharper lips are necessary, unless the slot is widened so as to 30 increase the bluntness of the lips, and in that case, the area of contact between the rolls and the glass in the slot is increased, which gives too great a chill and promotes 35 the formation of the mechanical ream heretofore referred to. The use of the smaller rolls, therefore, not only increases the life of the slot member, but also gives a product which contains less ream after the operation 40 has continued for a considerable period.

Fig. 4 illustrates a modification employing the same sizing rolls 17 and backing rolls 16, but having instead of the clay lips 26 of the Fig. 1 construction, the hollow members 27 which act as lips for the slot 28 and which are fluid cooled by the application of suitable circulating means. The use of these members avoids the difficulty as to wearing and crumbling away incident to 45 the clay lips, so that the cost of replacements and repairs is reduced and any contamination of the glass due to its washing action upon the clay is reduced to a minimum. The members 27 are preferably 50 made of a heat resisting composition, such as nichrome, and may be protected by circulating any suitable liquid or gas therethrough, it being undesirable to too greatly chill the glass at this point because of the 55 tendency to form ream as heretofore referred to.

What I claim is:

1. The combination with a glass tank having an outlet slot, of a pair of driven forming rolls in opposition to said slot with 60

the pass thereof under the head pressure of the glass in the tank, and a pair of supporting rolls engaging said forming rolls along the sides thereof opposite to said pass.

2. The combination with a glass tank having an outlet slot, of a pair of driven forming rolls in opposition to said slot with the pass thereof under the head pressure of the glass in the tank, means for 70 cooling said forming rolls, and a pair of supporting rolls engaging said forming rolls along the sides thereof opposite to said pass.

3. The combination with a glass tank having an outlet slot, of a pair of driven 80 forming rolls in opposition to said slot with the pass thereof under the head pressure of the glass in the tank, and a pair of driven supporting rolls engaging said forming rolls along the sides thereof opposite to 85 said pass.

4. The combination with a glass tank having an outlet slot, of a pair of forming rolls in opposition to said slot with the pass thereof under the head pressure of the tank, 90 a pair of supporting rolls engaging said forming rolls along the sides thereof opposite to said pass, means for driving the supporting rolls, and driving connections between the supporting rolls and the forming rolls.

5. The combination with a glass tank having an outlet slot, of a pair of driven forming rolls in opposition to said slot with the pass thereof under the head pressure 100 of the glass in the tank, a pair of supporting rolls engaging said forming rolls along the sides thereof opposite said pass, adjustable swinging arms in which the forming rolls are journalled, pivoted to swing around the 105 axes of rotation of the forming rolls so as to vary the width of said pass, and means for adjusting said arms and maintaining them in adjusted position.

6. The combination with a glass tank 110 having an outlet slot, of a pair of driven forming rolls in opposition to said slot with the pass thereof under the head pressure of the glass in the tank, a pair of supporting rolls engaging said forming rolls along 115 the sides thereof opposite said pass, adjustable swinging arms in which the forming rolls are journalled, pivoted to swing around the axes of rotation of the forming rolls, so as to vary the width of said pass, means 120 for adjusting said arms and maintaining them in adjusted position, means for driving the supporting rolls, and driving connections between the supporting rolls and forming rolls.

7. The combination with a glass tank 125 having an outlet slot, of a pair of driven forming rolls in opposition to said slot with the pass thereof under the head pressure of the glass in the tank, a pair of supporting 130

- olls engaging said forming rolls along the sides thereof opposite said pass, adjustable swinging arms in which the forming rolls are journalled, pivoted to swing around the axes of rotation of the forming rolls so as to vary the width of said pass, means for adjusting said arms and maintaining them in adjusted position, a frame in which the supporting rolls are journalled and means whereby said frame may be adjusted toward the tank.
8. The combination with a glass tank having an outlet slot, of a pair of driven forming rolls in opposition to said slot with the pass thereof under the head pressure of the glass in the tank, a pair of supporting rolls engaging said forming rolls along the sides thereof opposite said pass, a pair of bell crank levers at each end of the rolls pivoted at the axes of the supporting rolls and each having one arm in upright position with journals in such arms in which the forming rolls are mounted, adjusting means between the other ends of each pair of levers.
9. The combination with a glass tank having an outlet slot, of a pair of driven forming rolls in opposition to said slot with the pass thereof under the head pressure of the glass in the tank, a pair of supporting rolls engaging said forming rolls along the sides thereof opposite said pass, a pair of bell crank levers at each end of the rolls pivoted at the axes of the supporting rolls and each having one arm in upright position with journals in such arms in which the forming rolls are mounted, adjusting means between the other ends of each pair of levers.
10. The combination with a glass tank having an outlet slot, of a pair of driven forming rolls in opposition to said slot with the pass thereof under the head pressure of the glass in the tank, a pair of supporting rolls engaging said forming rolls along the sides thereof opposite said pass, a pair of bell crank levers at each end of the rolls pivoted at the axes of the supporting rolls and each having one arm in upright position with journals in such arms in which the forming rolls are mounted, adjusting means between the other ends of each pair of levers.
15. The combination with a glass tank having an outlet slot, of a pair of driven forming rolls in opposition to said slot with the pass thereof under the head pressure of the glass in the tank, a pair of supporting rolls engaging said forming rolls along the sides thereof opposite said pass, a pair of bell crank levers at each end of the rolls pivoted at the axes of the supporting rolls and each having one arm in upright position with journals in such arms in which the forming rolls are mounted, adjusting means between the other ends of each pair of levers.
20. The combination with a glass tank having an outlet slot, of a pair of driven forming rolls in opposition to said slot with the pass thereof under the head pressure of the glass in the tank, a pair of supporting rolls engaging said forming rolls along the sides thereof opposite said pass, a pair of bell crank levers at each end of the rolls pivoted at the axes of the supporting rolls and each having one arm in upright position with journals in such arms in which the forming rolls are mounted, adjusting means between the other ends of each pair of levers.

In testimony whereof, I have hereunto subscribed my name this 16th day of January, 1925.

HALBERT K. HITCHCOCK.
